JAMES MAZE KILNER, OF CHESTER, ENGLAND.

Letters Patent No. 80,075, dated July 21, 1868; patented in England, April 4, 1867.

IMPROVEMENT IN APPARATUS FOR TOWING VESSELS.

The Schedule referred to in these Letters Patent and making part of the same.

TO ALL TO WHOM IT MAY CONCERN:

Be it known that I, JAMES MAZE KILNER, of 3 Saltney Road, Chester, England, clerk, a subject of the Queen of Great Britain, have invented or discovered new and useful "Improvements in Apparatus for Towing Ships or Vessels;" and I, the said JAMES MAZE KILNER, do hereby declare the nature of the said invention, and in what manner the same is to be performed, to be particularly described and ascertained in and by the following statement thereof; that is to say—

The object of this invention is to supply apparatus, by means of which chains may be readily applied for the purposes of towing, and it is hoped thereby to avert the heavy wear and tear, and frequent casualties to life and limb, and valuable ships, incidental to "overall"-rope towing at sea.

My invention is represented in the accompanying drawings, of which—

Figure 1 is a deck plan, and

Figure 2 a vertical section of a vessel with such invention applied thereto.

Figures 3 and 4 are diagrams, exhibiting the mode of applying a towing-chain to a tug or towing-vessel, and one or two vessels to be towed thereby.

Figure 5 is a top view of the cleaver-trunk.

Figure 6 is a horizontal section of the "cleaver," or one-half of it.

Figure 7 is a view of the "grab-link," to be hereinafter described,

In carrying out my invention, I have what I term a cleaver-trunk extending down through the vessel, from its upper deck to and through its bottom, as shown at A in fig. 2, which is a contracted lengthwise section of a vessel's hull. This trunk receives a tube or cleaver, B, which in horizontal section is formed as represented, it being sharp in directions lengthwise of the hull, so as to cleave and pass through the water easily when the vessel is in motion either forward or backward. This cleaver I suspend within the trunk by means of ropes *a a*, led around sheaves so as to enable the cleaver to be depressed, so as to project below the keel of the vessel, or drawn up within the trunk, as occasion may require.

The towing-chain, after being fixed to a windlass or some other proper object on the deck, is to pass over a saddle or guide, *b*, (see fig. 5,) and thence down the trunk and the cleaver, and thence to the stern of the tug-vessel, where one of its links is to be hitched upon the tripping-hook *b* of the radial arm *c*, of a crane, *C*, arranged near the stern of the vessel, and so as to project above the deck in manner as represented. The arm *c* rests on a curved rail, *d*, supported by a counter-stem, *e*.

In fig. 6, the cleaver is shown in semi-section, that is, half of it, as formed with vertical grooves, which, when the two halves are put together, form vertical or tubular channels through the cleaver.

The external passages are to receive stay-chains *m m*, which, by being carried down through the cleaver, and through tubes *ff* going down through the hull, may be employed to support the cleaver while being drawn through the water.

In figs. 3 and 4, the cleavers are represented as projecting below the keels of the vessels, and as having stay and tow-chains applied to them. The tow-chains *m* are submerged or passed from the tug into the sea, and thrown underneath the hull of the vessel to be towed, and thence up through the cleaver thereof.

Where two vessels are to be towed, the chain may pass down the cleaver of one, to and up through that of the other.

Fig. 3 illustrates a frigate or vessel towing a monitor, with the tow-chains submerged, and going through the cleavers of the two vessels.

Fig. 4 denotes two vessels in tow of a steamer, with the tow-chains submerged.

The tripping-hook of the crane, formed as shown in the drawings, is hinged to the arm of the crane so as to be capable of being turned up or over, into the position represented in fig. 2 by dotted lines, the same being in order to discharge the towing-chain from the hook when it may be desirable to take in the chain.

While supporting the chain while a vessel is being towed thereby, the shank of the tripping-hook is to be held down to the arm of the crane by a pin passed through the arm and the shank.

The crane is free to turn laterally on the curved or quadrant-rail by which its arm is supported, and thus while the vessel is being towed by a chain hitched on the crane-hook, the towing-vessel will be free to move sideways more or less under the arm of the crane.

What is termed the "grab-link" is shown in fig. 7. One of these links may be fixed to a vessel near the keel and forefoot, the chain that goes out of the hawse-hole being passed through the said grab-link. The grab-link may be so used when there is no cleaver to the vessel, and when so employed, the grab-link is designed to bring the strain of the draught at or near the keel, rather than at the hawse-hole. This arrangement of the grab-link is shown in fig. 2.

The tow-chain is passed from the slip-hook above the taffrail and quadrant rail of the tug-vessel to the "cleaver" of the towed vessel, through one of the perforations or "alleys" of which the chain is drawn up to the deck, and there attached to a windlass or capstan, or, if preferred, its final link may be supported by the T-trigger, and thence slipped whenever needed.

The said trigger, shown at *t* in fig. 5, consists of a shaft extended across the mouth of the cleaver-trunk, and having an arm projecting laterally. This arm goes through the terminal link of the tow-chain, and rests on a bar, *s*, which, on being pulled from underneath the arm, will cause the discharge of the tow-chain from the arm.

The "cleaver" when greatly protruded, may be supported by chains passed up "alleys" placed at any convenient position between the garboard and bilge-streaks; the structure of the cleaver, however, may be of sufficient strength to require no stay-chains.

The cleaver may be used by heavy vessels when towing; its tendency, however, is to lift the screw of an ordinary tug, while, on the other hand, the "quadrant-rail" helps to keep it submerged.

When the towed vessel is not furnished with a cleaver, a low point of traction may be attained, as shown in drawing, fig. 2, where the cable used for towing is "frapped" down beneath the forefoot by the grab-link, supposed to be shackled to a chain passed from the deck at a point "broad on the port bow."

The grab-link may also be attached to a "messenger" passed through a "hawse-hole" beneath the quadrant-rail; thus the end of the tow-chain may be drawn from the towed to the tug vessel. The grab-link adheres to the chain about a fathom from its final link, and supports its weight until the latter is adjusted to the slip-hook on board the tug.

It should be observed that the grab-link may be made to "grab" a chain at any accessible point, whence it may be as readily detached by lifting its narrow end by a tripping-line or boat-hook. In this way it may be drawn up to the "slip-hook" after it has performed its purpose of hauling the chain up to the stern, while it is evident a messenger-rope "bent" on in the usual way could not be conveniently detached from the chain, as the "bend" would be too far astern of the vessel to admit of its being reached by hand, hence the grab-link, or some other appliance of equal utility, becomes a necessary appendage of the quadrant-rail. Further, the grab-link may also be used for adjusting a "spring," extended from the broadside to the tow-chain, on those rare occasions when it is necessary to tow at a greater angle than the quadrant-rail will permit.

In figs. 1 and 2, the grab-link is exhibited, also, as suspended by a line from the stern of a vessel. The tow-chain is to go through the grab-link, which, with its line, will serve to draw the chain up to the slip-hook.

The cleaver serves to keep the tow-chain free from contact with the keel and lower part of the hull of a vessel, while she may be pitching or rolling when at sea. Thus the cleaver operates to prevent damage to the sheathing or hull of a vessel, and is advantageous in other respects.

Having thus described my invention, what I claim, is as follows:

1. I claim the combination and arrangement of the cleaver and its trunk with the hull of a vessel, so that the cleaver may be operated as described.
2. I also claim the cleaver, constructed as represented in fig. 6, and as hereinbefore described.
3. I also claim the arrangement of the tow-chain, viz., so as to be fastened to a vessel near or below its keel, as set forth.
4. I also claim the combination and arrangement of the tow-chain and the cleaver of a vessel to be towed, such chain being passed through and out of the cleaver, as set forth.

J. M. KILNER,
Chaplain of Chester Castle.
